UNITED STATES PATENT OFFICE.

FRANK SCHMITZ, OF CHICAGO, ILLINOIS.

BANANA-SHIPPING CASE.

SPECIFICATION forming part of Letters Patent No. 643,163, dated February 13, 1900.

Application filed February 10, 1899. Serial No. 705,159. (No model.)

To all whom it may concern:

Be it known that I, FRANK SCHMITZ, a citizen of the United States of America, residing at Chicago, in the county of Cook and State 5 of Illinois, have invented certain new and useful Improvements in Banana-Shipping Cases, of which the following is a specification.

My invention relates to certain improvements in banana-shipping cases, the purpose 10 of which is to afford a package adapted to receive a bunch of bananas and hold the same in suspension in a covering or envelop of such material as to provide the necessary cushion and to support said envelop by means of a 15 rigid framework adapted to sustain and resist the blows and jars incident to ordinary means of transportation.

To such end the invention consists in certain novel characteristics, which will be fully 20 described below in connection with their preferred embodiment, and the essential features of which will be pointed out in the appended claims.

In the drawings presented herewith, Figure 25 1 is a side elevation of a complete package as the same appears when the goods are ready to ship. Fig. 2 is a vertical diametrical section showing the package open. Fig. 3 is a horizontal section looking downward in plane 30 3 of Fig. 2; and Fig. 4 is a perspective of a portion of the device, showing certain details thereof.

Referring to the drawings, A is a cylindrical crate, preferably barrel-shaped, formed 35 with any preferred number of top and bottom hoops a a' . An intermediate hoop a^2 is shown as permanently secured in position in Fig. 1; but the same is preferably left free to be raised or forced down upon the crate, as 40 seen in Fig. 2, except during the actual transportation of the goods, when it may be secured at some intermediate portion between the top and bottom of the crate by any suitable temporary means. The top and bottom hoops are 45 connected by a series of vertical slats a^4 .

A cylindrical bag B, which may be of ordinary construction, is suspended within the crate by means of a series of cords b , the bag being preferably smaller than the crate and 50 the cords being sewed into the bag and extending therefrom to the different members of the crate, preferably at the joints, and

stretched to put the bag under tension in all directions. This gives to the bag its cylindrical form of greatest extent and yet suspends it free from the crate far enough within the same to protect the inclosed goods from damage. The bag is preferably fastened with in the crate before the central or intermediate hoop a^2 is forced down upon the vertical slats, 60 and said slats are preferably longitudinal convex outward beyond the extent of the intermediate hoop, so that the forcing downward of said hoops straightens the slats and extends them longitudinally to stretch the bag 65 in the same direction. The bag is preferably open at the top, and after the goods are in place it is closed by suitable means, preferably by a series of cords C, tightly fastened to the closed end of the bag and stretched 70 therefrom to the crate and secured about the latter to center the tied end of the bag in its proper position. The lower end of the bag is preferably pointed toward the center, so as to center the goods, or rather the downwardly- 75 projecting stem, therein. This acts in conjunction with the centered upper end of the bag to partially suspend the openings from the two ends of the stem.

The advantages of the package are its great 80 simplicity, effectiveness, and cheapness of construction as well as its lightness and the thorough protection it affords to the inclosed goods.

It should be noticed that the bag B is slit 85 down substantially to the upper row of permanent cords, as is clearly shown in Fig. 2. This enables the bag to be lifted outward over the upper ring of the crate, which is larger than the top of the bag itself, thus leaving the 90 top of the package wide open and free for the insertion of the fruit.

I claim as new and desire to secure by Letters Patent—

1. The combination with a suitable crate, 95 of a bag suspended within and of contact with the crate by laterally-extending cords connecting its end portions with the corresponding end portions of the crate, and means for forcibly extending the crate longitudinally; 100 whereby tension is put upon the bag and its suspending-cords.

2. The combination with a crate consisting of end hoops connected by separated slats

bending outward at the middle, of a bag suspended in the crate and out of contact with its sides by cords extending laterally outward from its end portions, and means for forcing the middle portions of the slat inward and fixing them in the new position, whereby the bag and cords are subjected to permanent tension.

3. The combination with a crate consisting of separated longitudinal slats bulging outward at the middle, of hoops connecting corresponding ends of the slats, a bag suspended within the crate and out of contact therewith by cords connecting corresponding end portions of the bag and crate, and a hoop sliding upon the crate and having an inner diameter less than the normal outer diameter of the middle portion of the crate.

4. The combination with the open crate having spaced longitudinal members connect-

ed by transverse hoop members, of a bunch-inclosing bag shorter and of less diameter than the interior of the crate, and bag-suspending cords each looped about one of the inner members of the crate alongside an outer crossing member, having its loop branches sewed into the adjacent walls of the bag, and again looped around the same inner member upon the opposite side of said crossing outer member; whereby the bag is suspended at some distance within the lateral walls and end planes of the crate by cords protected from abrasion.

In witness whereof I have hereunto set my hand, at Chicago, in the county of Cook and State of Illinois, this 7th day of February, 35 A. D. 1899.

FRANK SCHMITZ.
